MAGNETIC SWITCH

George Lindley Usselman, Port Jefferson, N. Y.,
assignor to Radio Corporation of America, a
corporation of Delaware

Application January 27, 1938, Serial No. 187,124

7 Claims. (Cl. 200—98)

This invention relates to magnetic switches or contactors and especially to improvements on magnetic switches for saving or economizing in the use of electrical power used to operate the switch.

The practice in prior art has been to use one electro-magnet to close the switch and hold it closed. A comparatively powerful magnet is required to close the switch and hold it closed because of the large air gap present in the magnetic circuit. This air gap is necessarily and inherently large when the contactor or switch is open and the air gap is still comparatively large when the switch is closed. A comparatively large amount of iron is generally used for the magnetic circuit. For these reasons, a comparatively large amount of electrical power is required to operate the magnetic switch.

An object of this invention is to reduce the operating power required to hold the contactor closed.

Another object of this invention is to provide an auxiliary holding magnet which holds the contactor closed and further provides means for de-energizing the main armature magnet coil.

The present invention will best be understood by referring to the accompanying drawings, in which:

Fig. 1 is a front elevation of an improved contactor of this invention and an interlock switch which operates in conjunction with the magnets of the contactor; shown also in Fig. 4;

Fig. 1a is a side view of Fig. 1;

Fig. 1b is a partial plan view showing the auxiliary magnet;

Fig. 2 is a front elevation of another modification of this invention;

Fig. 2a is a side view of Fig. 2;

Fig. 3 is a front elevation of a further modification of this invention;

Fig. 3a is a side view of Fig. 3;

Fig. 4 is a side view of the interlock switch; and

Fig. 5 is a circuit diagram showing the switch contacts and coils of this invention.

Referring now in detail to the drawings:

The letter A indicates the main magnet core, B the main magnet armature, and C the coil of the main magnet contactor, all of which are mounted on a frame Fr. The armature B is mounted upon a movable member Ar which is pivotally arranged upon a shaft S. Armature B is provided with a stop ST which prevents the contactor from opening too far. Located upon the shaft S and insulated from it are a plurality

of circuit contactors 20, 21, 22 and 23, the numbers of which are not necessarily limited to four, but are only indicated as such to describe this invention.

To the lower portion of frame member Fr there is provided metallic supporting members 8, 9 and 10, which are bolted to the main contactor frame by means of a plurality of bolts 24. Two link toggle members 1 and 2 are supported by a bearing 3 located on the lower frame member 9, the upper portion of link 2 being pivoted to the armature Ar of the contactor by means of a pivot 25. A core D and coil F are supported as shown by means of two support members 7 which are bolted to the side frame member 8. An armature E is attached to toggle member 1 and by means of a pivot 26 is bolted to a bearing 6, the upper end of toggle member 1 being joined to toggle member 2 by means of a bearing 5 and pivot 27.

To the right of Fig. 1, there is shown an interlock switch which operates in conjunction with the main magnet armature. This interlock is mounted upon a panel near the end of the shaft S and for the sake of clarity is not shown in the side view Fig. 1a, but is described and illustrated in more detail by the side view Fig. 4. Arm 11 is attached to line up with the interlock switch on shaft S by an insulating bushing 13 and clamped by means of a U-bolt 12 and nuts 28. Arm 11 carries the adjustable pin 100 as shown, secured by nut 101. Interlock switch arm 14 is pivoted by pivot 29 on bearing 15, which is secured to the panel by means of a screw or stud 15a. Flexible lead 18 forms the electrical connection between the two. A leaf spring 16 is riveted to arm 14 by means of rivets 16a. The coil spring 17 is held in place by means of a stud 19 and nuts 19a. This stud also serves as a stop to prevent arm 14 from moving too far. The end portion 14' of arm 14 carries a contact 30. Stud 33 is bolted to the panel and carries a contact 31. The outgoing leads 41 and 42 are connected to studs 15a and 33a, as shown. Member 44 indicates the base of a bearing for one end of the shaft S.

In Fig. 1b, a plan view of the auxiliary holding magnet is shown. It will be noted that there are two toggle members 1 and 2 on each side. These two side members operate in parallel, the complete contact assembly being mounted upon the panel, as shown in Figs. 1 and 1a. Electrical connections are made from the coil C by means of leads L and from the coil F by leads L'.

Figs. 2 and 2a show another modification of

55

this invention wherein the auxiliary magnet coil F is mounted upon core D and supported by members H, while the armature E is connected upon the main contactor armature by means of members Q. This relay magnet has no air gap when the contactor is closed and its leverage is somewhat greater than that of the main magnet armature B.

Figs. 3 and 3a are still further modifications and somewhat different from Figs. 2 and 2a in that the auxiliary magnet core D is formed as part of the main magnet core A and the auxiliary magnet core E is also a part of the main magnet armature B, which in each case requires the addition of more magnetic material, such as iron to the main magnet core and armature. A slot 50 is cut across the face of the upper part of the main magnet core and coil F is placed upon the auxiliary coil core, as shown. The stop pin ST is located on the lower portion of the contact arm Ar, as shown, in order to prevent interference with the operation of coil F.

In the normal operation of an ordinary contactor or magnetic switch of the prior art type, the contactor is operated by some electrical control system which energizes the main magnet such as coil C. This pulls up and later closes the armature B, which is bolted to the arm Ar, the latter being clamped to shaft S, and causes the shaft to rotate through several degrees. Shaft S usually carries one or more contact fingers, such as is indicated by numerals 20 to 23, inclusive, which are insulated from the shaft but are generally part of some other external circuit 35 or circuits.

The operation of the improved contactor of this invention, as shown by Fig. 5, is different from that of the ordinary contactor in that when the contacts of the contactor are open, the interlock switch contacts 30 and 31 are closed by extension of spring 17. When the control current is applied from an external electrical control circuit, both magnetic coils C and F on the main and auxiliary magnets are energized and all contacts except 30 and 31 are closed. While the armatures B and E are open, practically all the pulling force for closing the contacts is applied by the main magnet. When the main armature B closes within about $\frac{3}{8}$ to $\frac{1}{4}$ " from the faces 50 of the magnet core A, the pin 100 touches the spring 16 of interlock switch arm 14; however, due to the inertia of arm 14, it does not move immediately, thus producing a slight time delay. The space between spring 16 and arm 14, as shown in Fig. 4, is made such that when the main contactor is closed, the contacts 30 and 31 can remain closed, in which case the spring 16 can be depressed but would not touch the arm 14. Due to the high velocity of main armature B, it will 60 close before the arm 14 of the interlock switch can open contacts 30 and 31 and as mentioned above, spring 16 will be depressed a greater distance. Now, since the main armature is closed, the toggle members 1 and 2 will cause the auxiliary armature E to also close; due primarily to the increased leverage of the toggle, and because the auxiliary magnet D and armature E has no large air gap, the pull of the small auxiliary magnet is sufficient to hold the main armature B. 65 of the contactor closed. After the contactor has closed, the depressed spring 16 overcomes the inertia of interlock arm 14 and the pressure of coil spring 17, and arm 14 is pressed down against the stop pin 19. This opens contacts 30 and 31, 70 which breaks the circuit of the main magnet coil

C so that it is no longer energized but auxiliary coil F is energized and holds all contacts except 30 and 31 closed. While the auxiliary coil F holds the contactor closed, it should be noted that the toggles 1 and 2 are not straight, otherwise the contacts would not open again. They should be set with an outward bend of several degrees to allow the contacts to open properly. Too much bend will require more holding force than is economical in the auxiliary holding magnet. When the external control voltage is removed, the auxiliary holding magnet releases the toggle and the contacts all open, which closes the interlock switch contacts 30 and 31 so that the main magnet is again ready for the closing 15 operation when an external control voltage is again applied. Of several contactors which were tested, it was found that the main contactor magnet normally used about sixty-five watts of power. By means of this invention, the power required 20 was reduced to above five watts. In particularly large contactors, where several hundred watts are required, this invention would permit a considerable saving.

The arrangements of this invention shown in Figs. 2 and 3 are simpler and have less moving parts than that shown in Fig. 1. Although the general principle of operation is the same in Figs. 1, 2 and 3, the arrangements shown in Fig. 2 and Fig. 3 will withstand operating wear much longer 30 than the arrangement shown in Fig. 1 and Fig. 1a.

The invention should not be limited to the modification shown as it is capable of taking other forms and shapes.

What is claimed is:

1. A magnetic contactor comprising a core member, a main armature pivoted with respect to said core member, an auxiliary armature located adjacent and linked to said main armature, a first magnetic coil mounted on said core member for moving said main armature, a second magnetic coil for moving said auxiliary armature, a movable shaft secured to said main armature, a plurality of switch contacts secured to said movable shaft, a switch member arranged near 45 said movable shaft and coupled thereto so that its contacts open to release the energizing voltage on said first magnet after said main armature is closed whereby voltage applied to said second magnetic coil holds said plurality of switch contacts closed.

2. A magnetic contactor comprising a core member, a main armature pivoted with respect to said core member, a toggle member linked to said main armature, an auxiliary armature located 55 adjacent and linked to said main armature by said toggle member, a first magnetic coil mounted on said core member for moving said main armature, a second magnetic coil for moving said auxiliary armature, a movable shaft secured to said main armature, a plurality of switch contacts secured to said movable shaft, a switch member arranged near said movable shaft and coupled thereto so that its contacts open to release the energizing voltage on said first magnetic coil 60 after said main armature is closed and said toggle member holding said plurality of switch contacts closed by the voltage applied to said second coil.

3. A magnetic contactor comprising a core member, a main armature pivoted with respect to said core member, a toggle member linked to said main armature, an auxiliary armature located adjacent and linked to said main armature by said toggle member, a first magnetic coil 70

mounted on said core member for moving said main armature, a second magnetic coil for moving said auxiliary armature, a movable shaft connected to said main armature, a plurality of switch contacts secured to said movable shaft, a switch member having time delay means arranged near said movable shaft and coupled thereto so that its contacts open to release the energizing voltage on said first magnetic coil after said main armature is closed and said toggle member holding said plurality of switch contacts closed by the voltage applied to said second coil.

4. A magnetic contactor comprising a core member, a main armature pivoted on said core member, an auxiliary armature located adjacent and linked to said main armature, a first magnetic coil for moving said main armature, a second magnetic coil for moving said auxiliary armature, said first and second magnetic coils both mounted upon said core member, a movable shaft secured to said main armature, a plurality of switch contacts secured to said movable shaft, a switch member arranged near said movable shaft and coupled thereto so that its contacts open to release the energizing voltage on said first magnet after said main armature is closed whereby the voltage applied to said second magnetic coil holds said plurality of switch contacts closed.

5. A magnetic contactor comprising a core member, a main armature pivoted to said core member, a pair of toggle members linked to said main armature, an auxiliary armature located adjacent and linked to said main armature by said toggle members, a first magnetic coil mounted on said core member for moving said main armature, a second core member, a second magnetic coil for moving said auxiliary armature and mounted on said second core member, a movable shaft secured to said main armature, a plurality of switch contacts secured to said movable shaft, a switch member arranged near said movable

shaft and coupled thereto so that its contacts open to release the energizing voltage on said first magnetic coil after said main armature is closed and said toggle member holding said plurality of switch contacts closed by the voltage applied to 5 said second coil.

6. A magnetic contactor comprising a core member, a main armature pivoted to said core member, a toggle member linked to said main armature, an auxiliary armature located adjacent 10 and linked to said main armature by said toggle member, a first magnetic coil for moving said main armature, a second magnetic coil for moving said auxiliary armature, a movable shaft secured to said main armature, a plurality of 15 switch contacts secured to said movable shaft, an arm insulatingly supported on said shaft, a switch member arranged near said arm insulatingly supported by said shaft so that its contacts open to release the energizing voltage on said 20 first magnet after said main armature is closed and said toggle member holding said plurality of switch contacts closed by the voltage applied to said second coil.

7. A magnetic contactor comprising a core 25 member, a main armature pivoted to said core member, a toggle member linked to said main armature, an auxiliary armature located adjacent and linked to said main armature by said toggle member, a first magnetic coil for moving said 30 main armature, a second magnetic coil for moving said auxiliary armature, a movable shaft secured to said main armature, a plurality of switch contacts secured to said movable shaft, a switch member located near said shaft and having a 35 spring element to provide a time delay so that its contacts open to release the energizing voltage on said first magnet after said main armature is closed and said toggle member holding said plurality of switch contacts closed by the voltage 40 applied to said second coil.

GEORGE LINDLEY USSELMAN.
